UNITED STATES PATENT OFFICE.

ALFRED C. HAFELY, OF BROOKLYN, NEW YORK.

SOLID BACK FOR BOOKS.

No. 823,168.

Specification of Letters Patent.

Patented June 12, 1906.

Application filed November 8, 1901. Serial No. 81,564.

To all whom it may concern:

Be it known that I, ALFRED C. HAFELY, a citizen of the United States, and a resident of the borough of Brooklyn, city of New York, 5 and State of New York, have invented new and useful Improvements in Solid Backs for Books, of which the following is a specification.

The object of my invention is to provide a book having great strength, so as to withstand the wear and tear of constant usage common with large books.

My invention consists in making a solid back of wood, metal, or other material and forming parallel grooves along the front of the solid back and crossing grooves on the opposite side of the solid back. The signatures or sections of the book are then fastened in the grooves on the front side of the solid 20 back. The cross-grooves have a sufficient depth to meet the parallel grooves located on the opposite side of the book-back. The meeting of the grooves located on the opposite sides of the back forms holes for fastening 25 the signatures to the book-back. Holes may also be formed in the book-back by an ordinary awl or other means. The covers are also secured to the solid back and a very durable book is thus formed.

Other features and advantages of my invention will appear from the specification and the drawings, in which the same letters of reference designate similar parts in all the figures.

Figure 1 illustrates an end view of the book. Fig. 2 represents one form of the solid back. Fig. 3 illustrates a detail used in connection with the solid back shown in Fig. 2 for strengthening the same. Fig. 4 illustrates a modified form of the solid back. 40 Fig. 5 illustrates the method of sewing the form of my book shown in Figs. 2 and 4. Figs. 6, 7, 8, 9, and 10 show the position of the thread after the book is sewed. Figs. 11 and 12 show another modification of my 45 device. Fig. 11 shows the parts of the solid back separated in order to illustrate the position of the thread in the sewed book. Fig. 12 shows the parts secured together.

The book A (illustrated in Fig. 1) has two 50 covers a' a'' , which are made of leather, canvas, cloth, or other material. These covers are glued or otherwise fastened to a back a^2 , which is made of some flexible material. The back a^2 is fastened by glue or other means to the solid back B. The form of the 55 solid back may be varied. It may be either

square, as shown in Fig. 5, or it may have the cross-section of a plano-convex lens, as shown in Fig. 2, or it may have a cross-section of a concavo-convex lens as shown in Fig. 4.

On the inner or exposed surface of the solid back B are formed grooves b^2 , running longitudinally thereof. They may be made by fastening strips to a back piece by gluing them thereto, or they may be formed by saw-cuts running the length of the back or by molding, according to the material of which the solid back is composed. In these grooves are secured the signatures e' e^2 e^3 , which 70 make up the book C. The grooves are of such a shape as to securely hold the edges of the signatures and at the same time to allow of the greatest possible flexibility in the leaves of the book. The grooves may be 75 square at the bottom with narrow ridges between them or they may be semicylindrical in shape. The signatures may be secured in the grooves by any of the well-known means of sewing a book, as by wiring them in or fastening them in by driving staples through the back of the signature into the solid back.

For the sewing of the signatures of the book holes may be formed in the solid back 85 to receive the wire, if it is wire-sewed or thread if it is sewed with thread. These holes may be made by an awl or a bit or by any well-known means, according to the material of which the solid back is composed. The thread or wire may then be passed 90 through the signatures and through the holes of the solid back and then tightly drawn and the ends fastened which secures the signatures in the grooves. To economically make the holes in the back constitutes one of the 95 features of my invention. This is accomplished by forming grooves b^3 b^3 b^3 across the back of the solid back and of such depth that they will meet the grooves running longitudinally along the front of the solid back, 100 thereby forming the holes at points where the crossing grooves intersect.

In order to strengthen the solid back and prevent longitudinal splitting if it is formed of wood, and also to prevent any possible 105 breaking or bending at the cross-grooves, a small piece b of wood, (shown in Fig. 3,) which is stamped or otherwise formed into the shape of the cross-groove in the back of a solid back, is inserted in the groove and securely fastened therein with glue. The grain of the wood of the piece runs along its length,

- and when the piece is placed in the groove the grain is at right angles to the grain of the wood of the solid back, and thereby splitting or breaking of the back is entirely avoided.
- 5 The cross-pieces also secure the threads used in sewing the signatures, since it will press against them when it is forced into place in the groove, and thus hold each of the signatures.
- 10 One of the methods by which the signatures may be fastened into the grooves is illustrated in Fig. 5. The ends of a cord c is passed through the holes b^4 b^{10} of the first groove and into the signature e' by the strands c^1 d^1 , and then to the center of the signature of the signature e' by the strands c^2 d^2 , then through the hole b^7 of the first groove by the strands c^3 d^3 . The first signature e' is then tightly drawn into the first groove. The ends of the cord are then passed through the hole b^8 , located at the center of the second groove, and into the center of the second signature e^2 by the strands c^4 d^4 , then to the ends of the second signature e^2 by the strands c^5 d^5 , then through the holes b^5 b^{11} of the second groove by the strands c^6 d^6 , and the second signature is then tightly drawn into place. The cord is then passed into the holes b^6 b^{12} of the third groove and into the back of the third signature e^3 by the strands c^7 d^7 , to the center of the third signature by the strands c^8 d^8 , and through the hole b^9 by the strands c^9 d^9 , and so on until all the signatures have been fastened in the book. The strands of the single cord are then securely fastened by any well-known means, such as tying the ends thereof or by turning the ends into the cross-grooves and securing them by forcing the glued strip against them when it is inserted in the cross-grooves of the solid back. Practically the same sewing may be accomplished by passing a cord through a hole in one end of a longitudinal groove and through the signature in that groove, then to the center of the signature and through the signature and the center hole of the same groove. The first signature is then tightly drawn into place. The cord is then passed into the center hole of the next groove through the next signature, along that signature to the end hole of the same groove, and the second signature is then drawn into place. The cord is then passed into the end hole of the third groove and to the center of the book, and so on until all the signatures have been fastened in the book. The same may then be done at the other end of the book, whereby the other end of each of the signatures is also fastened to the solid back. The ends are then fastened as before.
- 65 The steps stated above may be further varied by fastening the center of the cord by any well-known means in the center cross-groove at the back or by looping it over the outside ridge of the first groove in the manner

shown in Fig. 10. The cord may be passed through the center hole of the first groove and into the center of the first signature, and then through the back of the first signature at each end and into the holes of the first groove, and then into the end holes of the second groove, and so on.

In the modification illustrated in Figs. 11 and 12, O is an oblong piece having on its front a number of grooves b^2 between the ridges b' . Transverse grooves o^1 , o^2 , o^3 , and o^4 are cut in the back and to such a depth that they will just reach the longitudinal grooves b^2 on the front of the oblong piece. Holes will thus be formed through the oblong piece, as described above. The signatures e' , e^2 , and e^3 are placed one by one into the longitudinal grooves b^2 and sewed to the piece O . This is done by passing a threaded needle through the hole o^5 and into the first signature e' , then back through the hole o^6 , forward again through the hole o^7 into the signature, then back through the signature and the hole, and the first signature is then tightly drawn into place. The second signature e^2 is then placed in the next longitudinal groove and the threaded needle is passed through the hole o^8 into that signature, then back through the signature and the hole o^{10} , then forward through the hole o^{11} , and so on up and down the grooves until all the signatures are sewed. The oblong piece O is made solid and secure against any possible breaking or bending at the transverse grooves by fitting and gluing into the grooves the cross-pieces p^1 , p^2 , p^3 , and p^4 . Since the grain of the pieces p^1 , p^2 , p^3 , and p^4 is parallel with their axes, they will prevent the splitting of the oblong piece O . To further secure the solid back thus formed, there is glued or otherwise secured to its back the piece Q , having a plano-convex cross-section. This gives a finished exterior to the solid back and secures all its parts together. By fastening the cross-pieces p^1 , p^2 , p^3 , and p^4 in the back grooves and the piece Q to the back of the threads which hold the signatures the signatures are independently secured, so that if a signature should be torn out and its supporting-thread broken, the remaining signatures will still be securely held by their threads to the solid back. Other variations may be made in the parts of my book without in any way departing from the spirit of my invention.

What I claim as new, and desire to secure by Letters Patent, is as follows:

1. A rigid book-back provided on its inner surface with a series of longitudinal grooves and on its outer surface with a series of cross-grooves.

2. A rigid book-back provided on one side with a series of longitudinal grooves and on the opposite side with a series of cross-grooves sufficiently deep to meet the longitudinal grooves.

3. The combination of a rigid book-back having a series of longitudinal grooves and a series of cross-grooves and signatures fastened in said longitudinal grooves by a strand passing through the said cross-grooves.

4. The combination with a rigid book-back having a series of longitudinal grooves on its inner surface and cross-grooves on its outer surface of sufficient depth to meet the grooves of the inner surface, a strand for fastening the signatures into the said grooves and strips inserted into the said cross-grooves for strengthening the back.

15 5. The combination of a pair of book-covers, a solid back fastened thereto and having a series of longitudinal grooves on the inner surface thereof and on the outer surface cross-grooves; and having a series of 20 holes in said grooves, signatures fastened in the grooves by threads passing through the said holes, and strips in said cross-grooves for securing the said threads.

6. In a book the combination of a solid 25 back having longitudinal grooves and a series of holes in each of said grooves, signatures fastened in said grooves by a continuous cord passing through one of the holes and through a signature in each of said 30 grooves, and back through the signature and another of said holes in the groove and through a hole and signature in the next groove.

7. In a book the combination of a solid 35 back having longitudinal grooves and a series of holes in each of said grooves, signatures fastened in said grooves by a continuous cord passing through one of the holes and signature in each of said grooves and 40 back through the signature and another of said holes in the groove and through a hole and the signature and back through the signature and a hole and then through a hole and signature in the next groove whereby 45 both ends of the signature are secured.

8. In a book the combination of a solid back having a number of longitudinal grooves on one side and cross-grooves on the opposite side, and a strip fastened to the back of the said solid back for increasing its 50 strength.

9. In a book the combination of a solid back having a number of longitudinal grooves on one side and cross-grooves on the opposite side and a strip fastened to the 55 back of the said solid back and extending throughout its length for increasing its strength.

10. In a book the combination of a solid back having a number of longitudinal 60 grooves on one side and cross-grooves on the opposite side, and cross-pieces inserted in said grooves and a strip fastened to the back of the said solid back for increasing its strength.

65 11. In a book the combination of a solid back having a number of longitudinal grooves on one side and cross-grooves on the opposite side and of sufficient depth to meet the longitudinal grooves, and signatures located in the longitudinal grooves and held by stitches passing through the cross-grooves, cross-pieces located in said cross-grooves and a strip fastened on the back of the solid back for increasing its strength.

70 12. In a book the combination of a pair of covers, a solid back having a series of parallel grooves, and holes in said grooves and signatures held in said grooves by stitches passing through said holes and a strip fastened to the back of the solid back for securing the said stitches.

In testimony whereof I have signed my name to this specification in the presence of two subscribing witnesses.

ALFRED C. HAFELY.
